DRIVE MECHANISM

Nathan M. Lower, Tuckahoe, N. Y., assignor, by
mesne assignments, to The Standard Stoker
Company, Inc. (1922), New York, N. Y., a cor-
poration of Delaware

Original application July 2, 1928, Serial No.
289,774. Divided and this application Decem-
ber 20, 1933, Serial No. 703,198

3 Claims. (Cl. 74—422)

My invention relates to mechanical stokers, and especially pertains to stokers for locomotives and the like.

This application is a division of my co-pending application, Serial No. 289,774, filed July 2, 1928, for Locomotive stoker, Patent No. 1,947,723, granted February 20, 1934.

The main object of the present invention is the provision, in locomotive stokers of the class 10 employing a conveyor extending from the tender to the locomotive firebox, of power drive mechanism of a compact and durable construction, rigidly secured to the locomotive frame underneath the conveyor of the stoker and being separate and apart therefrom, thus permitting power drive mechanism or the parts thereof to be easily removed for the purpose of repair and replacement.

More specific objects of the invention reside 20 in the particular arrangement of and relation between the elements of the stoker conveyor and the power drive mechanism, as will appear from the following specification taken in connection with the accompanying drawings and the claims 25 annexed thereto.

While, without exceeding the scope thereof as defined in the appended claims, my invention may be embodied in numerous constructional forms, I have described one form thereof, by 30 way of example, in the following specification, and shown the same in the accompanying drawings, in which:

Fig. 1 is a plan of a locomotive stoker constructed in accordance with my invention, shown 35 as applied to a locomotive, the fire box of which is indicated in section, the locomotive cab deck and the tender being omitted;

Fig. 2 is a plan view of the power drive mechanism with some parts in section and other parts 40 removed to best illustrate the construction;

Fig. 3 is a section taken on the line 3—3 of Fig. 2;

Fig. 4 is a section taken on line 4—4 of Fig. 2;

Fig. 5 is an elevation of the conveyor reverse 45 mechanism with the cover removed showing the ratchet wheel and pawl mechanism; and

Fig. 6 is a section taken on the irregular line 6—6—6 of Fig. 2.

The form of stoker herein chosen for description 50 and illustration comprises a tender conduit, the rear portion, 2A, of which is trough shaped and is disposed beneath the fuel hopper of the tender. The conduit is mounted in any well known manner so as to be capable of sliding longitudinally with respect to the tender.

The front end 2E of the tender conduit is enlarged, at 2D, and is formed, beyond such enlargement, so as to produce the ball member 2C of a hollow ball and socket joint. The ball member 2C enters a corresponding socket portion 8 5 formed at the rear end of a riser conduit 3, a removable cap 38 being associated with the socket portion 8 to complete, with the latter and the ball portion 2C, a ball and socket connection between the tender conduit and the riser conduit 3.

A fuel conveyor screw 7 is rotatably mounted in the tender conduit, and is driven, from its rear end, through gearing 7A by means of a flexible shaft 7B connected by a telescopic and 15 universal joint with a power drive mechanism 40 which will be hereinafter described in detail. A crusher 20 cooperates with the conveyor screw 7 to reduce large lumps of fuel to a size more suitable for efficient firing. The tender conveyor 20 screw 7 drives a second conveyor screw (not shown) which is rotatably mounted in the riser conduit 3 and delivers fuel onto the distributor plate 5 located at the firing opening 2 of the firebox 1 and from which plate the fuel is spread 25 over the firebed. Adjustable wings or vanes 25 control the flow of fuel to the plate 5.

The power drive mechanism 40 comprises a motor of the single cylinder type, the cylinder 70 of which houses a piston 15 which is reciprocable therein to operate a piston rod 71. Secured to the piston rod 71 is a rack gear 41 which is mounted to reciprocate in a housing 40A. At a point remote from the cylinder 70, the housing 40A is apertured as at 90 and a gear 42 is disposed in the apertured portion and is engaged by the rack gear 41. A cover casting 49 is secured to the top wall portion of the rack housing 40A and is provided with a depending flange 89 which forms a closure for the rearward side of 30 said housing which is open to permit machining thereof. A portion of this cover casting 49 is provided with a collar 91 which fits over the gear 42 and forms the lower portion of a bearing 72 for the shaft 61 on which the gear 42 is mounted. 35 A second cover casting 60 is placed over the gear 42 and the shaft 61 and is bolted securely to the first named cover casting 49 and forms therewith a casing for the gear 42 and the other portion of the bearing 72 for the shaft 61.

The shaft 61 extends rearwardly of the gear 42 toward the tender and lies transversely to the rack gear 41. On the rearward portion of the shaft 61 a ratchet wheel 43 is mounted and is engaged by pawls such as 44 carried by the pawl 55

casing 45. As the rack gear 41 reciprocates in the housing 40A, the gear 42 rotates first in one direction and then in another direction. Motion is transmitted to the pawl casing 45 during one 5 stroke of the piston 15, while during the other stroke, the pawl casing idles. The direction of rotation of the pawl casing 45 is determined by the setting of the pawls 44; the setting of these pawls may be changed at will by the cam shifting collar 16 (Figure 4). The pawl casing is covered by a plate 73 which is firmly secured to the pawl casing 45 and has formed therewith lugs 62 which form one element of a universal joint 74 for driving the flexible shaft 1B. The power 10 drive mechanism 40 passes underneath the riser conduit 3 transversely to the locomotive and is rigidly secured to the frame F by suitable bolts 15 passing through the flanges 48 and 56 of the housing 40A and the cover casting 49 respectively. The power drive mechanism is not secured to the riser conduit 3 in any manner and thus whenever it is necessary to overhaul or 20 repair the drive mechanism, it is only necessary to loosen the bolts which hold the drive mechanism 25 to the frame F. Such a construction greatly expedites repair work and is of great benefit to the railroads in properly maintaining the stoker in a good state of repair.

From the foregoing, it will be apparent that a 30 novel stoker power drive mechanism has been constructed. The construction and relation of parts of this drive mechanism is such that it can be cheaply maintained in good running order.

I claim:

35 1. The combination including a reciprocable rack gear, a housing for said rack gear, said housing being open along one side thereof and having an aperture in its top wall, an attachment flange formed with the said housing opposite its 40 open side and extending outwardly therefrom in a direction away from said open side, a cover having a plate-like portion closing the open side of said housing and a plate-like portion extending across the top wall of said housing, an 45 attachment flange extending outwardly from said cover in a direction opposite said first named flange, said cover having an opening registering with the aperture in said housing top wall, a collar formed with said cover embracing the 50 said opening, a member formed with said collar extending transversely of said rack gear, said

member forming the lower portion of a bearing, a shaft mounted in said bearing member, a gear mounted on said shaft in said collar engaging said rack gear, a second cover surmounting said collar and forming with said collar a casing for 5 said gear, and a member formed with said second named cover forming the upper portion of a bearing for said shaft.

2. The combination including a reciprocable rack gear, a housing for said rack gear, said 10 housing being open along one side thereof and having an aperture in its top wall, an attachment flange formed with the said housing opposite its open side and extending outwardly therefrom in a direction away from said open side, a cover 15 having a plate-like portion closing the open side of said housing and a plate-like portion extending across the top wall of said housing, an attachment flange extending outwardly from said cover in a direction opposite said first named 20 flange, said cover having an opening registering with the aperture in said housing top wall, a member formed with said cover adjacent the opening therein extending transversely of said rack gear, said member forming the lower portion 25 of a bearing, a shaft mounted in said bearing member, a gear mounted on said shaft within the confines of the opening in said cover engaging said rack gear, a second cover embracing the opening in said first named cover and forming a casing for said gear, and a member formed with said second named cover forming the upper portion of a bearing for said shaft.

3. A cover for a rack gear housing which includes, when in operative position, a flat top 35 wall, a wall depending from said top wall forming a side wall for said housing, an attachment flange extending outwardly from said depending wall in a direction opposite with respect to said top wall, said top wall being provided with an 40 aperture, a collar rising above said top wall and bounding said aperture, a member extending outwardly from said collar in a direction approximately perpendicular to the plane of said depending wall, said member forming the lower 45 portion of a bearing, a second cover surmounting said collar, and a member formed with said second named cover forming the upper portion of said bearing.

NATHAN M. LOWER. 50
